UNITED STATES PATENT OFFICE.

JAMES ROBERTSON, OF MONESSEN, PENNSYLVANIA, ASSIGNOR TO PITTSBURGH STEEL COMPANY, OF PITTSBURGH, PENNSYLVANIA, A CORPORATION OF PENNSYLVANIA.

DEVICE FOR PACKING NAILS AND LIKE ARTICLES.

1,187,098.

Specification of Letters Patent. Patented June 13, 1916.

Application filed July 31, 1915. Serial No. 42,992.

To all whom it may concern:

Be it known that I, JAMES ROBERTSON, a citizen of the United States, and resident of Monessen, in the county of Westmoreland and State of Pennsylvania, have invented a new and useful Improvement in Devices for Packing Nails and Like Articles; and I do hereby declare the following to be a full, clear, and exact description thereof.

10 My invention relates to a device for packing nails or like articles in kegs or other receptacles, the object of my invention being to provide a device of this character by means of which the nails will be discharged 15 into the keg in such position that each nail lies substantially parallel with the other, so as to be packed close together, making it possible to ship a great many more nails in the ordinary sized keg, than where the nails 20 are discharged into the keg irrespective of their position one with the other and leaving a great deal of waste space between the nails.

By my invention, I provide a support for 25 the keg, which is adapted to elevate the keg up in position with a discharge hopper or chute so that said hopper extends down into the keg, said hopper containing means for bringing the nails into parallel, or substantially parallel, position so that they are discharged into the keg in this way, and means 30 for providing for the lowering of the keg as it is gradually filled, the hopper remaining stationary. In this way the keg is lowered 35 as it is filled and when completely filled, passes below the hopper so as to be readily removed and another one inserted in its place.

In the accompanying drawings, Figure 1 40 is a side elevation partly in section of my improved device; Fig. 2 is a vertical section of the keg, the discharge hopper, and the support for the keg; and Fig. 3 is a cross-section on the line 3-3, Fig. 1.

45 In the drawing, the numeral 2 designates a tank for containing water or other suitable liquid. A float 3 is contained within said receptacle, said float being connected with the rod 4, which may be in the form of a 50 pipe, and which extends out through the opening 5 of said tank. Connected to the rod 4 is the yoke-member 6 provided with the arms 7. These arms form the support for the suspended platform 8, said platform being supported on the swinging mem-

bers 9, which are suspended from the arms 7. The yoke-member is guided by the guides 6a.

The platform 8 has the extension 10 with the bearing 11, which engages the vertical shaft 12, said shaft forming a guide for said platform in its upward and downward movement, as will more fully hereinafter appear.

A clamping ring 11a is adapted to surround the keg, said clamping ring having the swinging sections 11b adapted to be connected by the thumb-screw 11c.

The shaft 12 is mounted in the foot 13 which slides on the receptacle 2, and the upper end of said shaft forms the support for the feeding-hopper or chute 14, said hopper having the socket 15 into which said shaft fits. This feed-hopper or chute 14 has the mouth 16 into which the nails are discharged from the hopper 17. The throat portion 18 of the hopper 14 has the inclined plates 19 and 20, which deliver the nails to the contracted opening 21 leading into the main portion of the hopper. The lower portion 22 of the hopper 14 is divided by the partition 23, as indicated in Fig. 2, and in addition, there are the shorter partitions 24 at the bottom of the chute, said partitions being preferably of varying height and forming the slotted openings 24a. The purpose of these partitions is to cause the nails to pass from the bottom opening of said chute in practically parallel relation to each other, so that they will enter the keg in this 90 position and so provide for the close contact of the nails one with another, and the packing of a greater number in the keg.

It will be found desirable in packing nails in a device of this character to have the keg 95 and the feeding chute vibrate so as to provide for the proper distribution of the nails by the partitions 24, and the closer relation of the nails one with another when they pass into the keg. It is on the same principle as when a barrel of any loose material is jarred or shaken so as to compact the contents. Accordingly I provide for this jar-ring or vibrating of the keg and hopper, and to this end a rod 25 is connected up to a 100 suitable source of power, whereby reciprocating movement is imparted to said rod, and connected to the rod 25 is the arm 26, and at the outer end of said arm is secured the rock-shaft 27. The rock-shaft 27 car- 110

ries the rocker-arm 28, which is adapted to engage the seat 29 in the bracket 30, which is connected to the vertical shaft 12. A bar 31 connects the arm 26 with the arm 32, which is secured to the rock-shaft 33, the rocker-arm 34 engaging the bracket 35 on the shaft 12.

In packing nails with my improved device, the keg 36 is adjusted on the platform 10 8 by lowering said platform, as indicated in dotted lines Fig. 1, whereupon the float 3 will lift the platform and keg carried thereby up into position indicated in full lines Fig. 1, and in this position of the keg, the 15 hopper 14 will be inside the keg and its lower end well down to the bottom of the keg, as indicated in Fig. 2. The nails are then introduced into the hopper 17, and passing therefrom are discharged by the 20 plates 19 and 20 through the inlet 21 into the main body of the hopper. The mass of nails thus introduced is divided by the partition 23. The nails pass down through the 25 chute and come in contact with the partitions 24, which act to bring the nails into practical parallel position with each other. By having some of the partitions 24 higher than others, the bridging of the nails from one partition to another is prevented, and 30 the clogging up avoided. The nails pass from the hopper into the keg in the position in which they are discharged from said hopper; and, at the same time, the hopper and keg are vibrated by the action of the 35 reciprocating rod 25. This jarring action acts to cause the nails to settle closer together in the keg, and as the nails enter the keg the weight thereof acts gradually to lower the keg, the float 3 sinking down in 40 the water of the tank 2. This downward movement of the keg is gradual, and the resistance offered by the float is in proportion to the weight of the nails, so that when the keg has been filled to its capacity, the float 45 will have been lowered to a point where the keg will have passed below the lower end of the hopper 14, as indicated in dotted lines, Fig. 1, and in position to be removed from the platform.

50 It is apparent that a device of this kind may be arranged in series, one beside the other; and the kegs can be arranged to be at

different stages of being filled so that one operator can attend to several machines.

While I have illustrated the tank and 55 float therein as a desirable and convenient way of raising and lowering the keg, it is apparent that other means may be employed for this purpose if desirable.

What I claim is:

60 1. In a device for packing nails or like articles, the combination of a support for the keg, a receptacle for liquid, a float in said receptacle, connections between said float and said support, and a chute in line with said support and adapted to enter the keg supported thereon when said support is raised.

65 2. In a device for packing nails or like articles, the combination of a support for the keg, means for raising said support, a chute in line with said support and adapted to enter the keg when elevated, and means for vibrating said chute and keg.

70 3. In a device for packing nails or like articles, the combination of a support for the keg, means for raising said support, a chute in line with said support adapted to enter the keg when elevated, a vertical shaft engaged by said support and carrying said 75 chute, and means for moving said shaft back and forth in a plane at right angles to its axis.

75 4. In a device for packing nails or like articles, the combination of a support for the keg, a chute adapted to enter the keg, and partitions of unequal height in said chute forming slotted openings through which the nails are discharged into said keg.

80 5. In a device for packing nails or like articles, the combination of a support for the keg, a chute adapted to enter the keg, said chute having at its upper end a contracted inlet, a partition dividing said chute, and a series of shorter partitions forming 85 slotted openings for the discharge of the nails into the keg.

85 In testimony whereof, I the said JAMES ROBERTSON, have hereunto set my hand.

JAMES ROBERTSON.
